UNITED STATES PATENT OFFICE.

WYATT BOYD, OF DAYTON, OHIO.

GAS-ENGINE.

1,345,345.

Specification of Letters Patent.

Patented July 6, 1920.

Application filed January 4, 1919. Serial No. 269,643.

To all whom it may concern:

Be it known that I, WYATT BOYD, a citizen of the United States, residing at Dayton, in the county of Montgomery and State of Ohio, have invented a new and useful Gas-Engine, of which the following is a specification.

This invention relates to explosive engines one of its objects being to provide a two cycle engine which is simple and compact in construction having interfitting relatively movable pistons provided with novel means whereby the said pistons are caused to work in properly timed relation to take in the 10 gas, compress it, receive the force of the explosion, and exhaust the gas.

With the foregoing and other objects in view which will appear as the description proceeds, the invention consists of certain 20 novel details of construction and combinations of parts which will be hereinafter more fully described and pointed out in the claims, it being understood that various changes may be made in the construction 25 and arrangement of the parts without departing from the spirit or sacrificing any of the advantages of the invention as set forth in the appended claims.

In the accompanying drawings the preferred form of the invention has been shown.

In said drawings—

Figure 1 is a section through the engine and showing the positions of the pistons at the completion of the compression stroke 35 or at the beginning of the power stroke.

Fig. 2 is a similar view showing the positions of the parts at the end of the power stroke.

Fig. 3 is a similar view showing the positions of the pistons at the completion of the exhaust operation and at the beginning of the compression stroke.

Fig. 4 is a section on line 4—4, Fig. 1, the piston and its operating mechanism being shown in elevation.

Referring to the figures by characters of reference, 1 designates the cylinder of the engine having an inlet port 2 in one end and an exhaust port 3 in one side, the inlet 50 port being provided with a suitable valve, not shown. A crank shaft 4 is mounted for rotation in the crank case 5 and has a pitman 6 connecting it with an inner piston 7. This piston is mounted for reciprocation and fits snugly within a hollow outer 55 piston 8 provided in the exhaust side thereof

with exhaust openings 9. The active end of the piston 8 is closed while the other end thereof is connected by a toggle 10 with the base of the case 5. A link 11 connects 60 the intermediate joint of the toggle with the crank of the shaft 4 so that, during the rotation of the crank, the link will work the toggle back and forth and cause the piston 8 to reciprocate in properly timed relation with the piston 7 therein. The spark plug 12 of the engine is preferably located in a recess 13 in the cylinder at one side of the end of piston 8 when at the end of its compression stroke.

Assuming that the explosive charge is compressed, it will be contained in the space between the ends of the pistons 7 and 8 and between piston 8 and the head of the cylinder as shown in Fig. 1. As the recess 13 is 70 in communication with both of these spaces the charge, when ignited, will drive the inner piston 7 downwardly and cause the crank shaft to rotate as indicated by the arrow in Fig. 1. Link 11 will, during the 75 first half of the rotation of the shaft, move the outer piston 8 slightly toward and then back away from the head of the cylinder and at the same time, the inner piston 7 will move downwardly under the force of the explosion to the position shown in Fig. 2. During the third quarter of the rotation of the shaft 4 the crank will thrust through the link 11 against the toggle and cause the outer piston 8 to move downwardly relative to the inner piston, bringing the ports or openings 9 into communication with the 80 exhaust port 3 and causing the burned gases to be expelled from between the approaching piston heads. At the same time a charge of 85 fresh gas will be drawn into the cylinder by the descending piston 8, so that the engine will be recharged and the burned gases exhausted on the completion of the third quarter of the rotation, as shown in Fig. 3. The 90 completion of the rotation of the shaft 4 will result in the simultaneous upward movement of the two pistons and the compression of the gas in the end of the cylinder until the parts reach the positions shown in Figs. 95 4 and 1 whereupon the operation described 100 will be repeated.

What is claimed is:—

In a two cycle engine the combination 110 with a cylinder having an end inlet and a side exhaust, of an outer hollow piston having side openings movable into communica-

tion with the exhaust port, an inner piston within and movable relative to the outer piston, a crank, a toggle anchored at one end and connected to the outer piston at its 5 other end, a link connection between the crank and the toggle, and a pitman connection between the crank and the inner piston.

In testimony that I claim the foregoing as my own I have hereto affixed my signature in the presence of two witnesses.

WYATT BOYD.

Witnesses:

LOUIS STINAL,

CHARLES H. WISEMAN.
